Primary Examiner — Austin Murphy*(74) Attorney, Agent, or Firm* — Volpe Koenig(57) **CLAIM**

I claim the ornamental design for a display terminal, as shown and described.

DESCRIPTION

FIG. 1 is a top, front, left perspective view of a display terminal in accordance with a first embodiment of my design;

FIG. 2 is a front elevational view thereof;

FIG. 3 is a left side elevational view thereof, the right side elevational view being a mirror image thereof;

FIG. 4 is a rear elevational view thereof; and,

FIG. 5 is a top plan view thereof.

The broken lines shown represent portions of the display terminal that form no part of the claimed design.
